UNITED STATES PATENT OFFICE.

ORVEY PRICE, OF PLAINFIELD, NEW JERSEY, ASSIGNOR, BY MESNE ASSIGNMENTS, TO TAYLOR IRON & STEEL COMPANY, OF HIGH BRIDGE, NEW JERSEY, A CORPORATION OF NEW JERSEY.

SAFE OR VAULT DOOR BOLTING MECHANISM.

No. 821,740.

Specification of Letters Patent.

Patented May 29, 1906.

Application filed October 10, 1904. Serial No. 227,781.

To all whom it may concern:

Be it known that I, ORVEY PRICE, a citizen of the United States, residing in Plainfield, in the county of Union and State of New Jersey, have invented certain new and useful Improvements in Safe or Vault Door Bolting Mechanism, of which the following is a specification.

The present improvement relates to safe or vault door bolting mechanism, an object of the invention being to provide improved bolting mechanism which will effectively draw or wedge the door into its seat and hold it in such position without the bolts being under constant tendency to retract or creep back to their retracted position.

A further object is the provision of improved bolting mechanism the bolts of which when shot out are by their position effectively blocked against retraction by vibration or concussion.

A further object is the provision of bolting mechanism in which a number of safeguards against the premature retraction thereof are provided.

The present mechanism is in part an improvement upon that shown and described in the contemporaneously-pending application of Walter Gaston and myself, Serial No. 202,491, now Patent No. 792,072, dated June 13, 1905, and my application Serial No. 209,156, filed May 23, 1904, in which rim-dogging bolts are used for locking the bolts in their protracted position substantially similar to that herein shown and described and is also an improvement in part upon the subject-matter of the several patents for bolting mechanism granted to Henry D. Hibbard. In those patents the bolts when protracted have their inner ends in position to engage a boss carried by the door. In practice, however, it was not found desirable to protract the bolts sufficiently far so that they would be in a dead-center position, in

which position the boss would have had superior effectiveness, since when in such position difficulty would have been experienced in starting them back when it was necessary to open the safe. In the present improvement, however, the bolts are thrown not merely to a dead-center position, but beyond their dead-centers, so that being off their

dead-center position they can be easily started, while the boss has even greater effectiveness in the present organization than in the said patented structures, since the bolts cannot be jarred away from such boss in the direction in which they must move in order to be retracted. It has also been found desirable to relieve the bolts from the tension and strain under which they were placed when tapered ends thereof engaged, during the entire time the door was bolted in its seat, the walls of the bolt-openings in the jamb, for the reason that the bolts in such an organization have a constant tendency to return to their initial position, and thus open the safe, since owing to such tapered formation when the door was subjected to vibration the bolts tend to slip away from the jamb, this having been only prevented by some suitable additional lock or dogging means. In the present instance the construction is such that while the bolts have the same drawing-in function as is present in those patents, yet when the door is firmly seated the bolts are relieved of any appreciable tendency to return to their starting position, while the door, however, remains under tension, and therefore in firm engagement with its seat, so that a metal-to-metal tight joint is obtained and maintained.

In the drawings accompanying and forming a part of this specification, Figure 1 is a rear view of a door, showing this improved bolting mechanism. Fig. 2 is a cross-sectional view thereof, taken in line *a a*, Fig. 1. Fig. 3 is a diagrammatic view illustrating the positions of a bolt during its protraction. Figs. 4, 5, and 6 also illustrate the different positions of a bolt during the protraction thereof.

Similar characters of reference indicate corresponding parts in the different figures of the drawings.

This improved bolting mechanism may be applied to various forms of safe or vault doors, but is particularly applicable to that form of door comprising a body 2, having a rearwardly-extending flange 3, forming a chamber 4, in which the bolting mechanism may be located, which chamber is closed by a back plate 5, secured to the door in any suitable manner, as by means of bolts, which

when the door is made of unmachinable metal may project into soft-metal inserts located in the flange.

The bolting mechanism comprises a series 5 of bolts 6, located to project around the door, which in the present instance is shown as circular, the inner ends of which are pivotally connected to a rocking plate 7, having worm-teeth 8, in mesh with a worm-shaft 9, suitably supported in bearings. This shaft carries at one end a bevel-gear 10, fixedly secured thereto, which is in mesh with a bevel-gear 11, loosely mounted upon a spindle 12, which projects through the door with its inner end suitably supported by a removable cap 13, carried by the back plate. For effecting connection between this loosely-mounted bevel-gear and the spindle so that on the turning of the latter the worm-shaft 15 will be rotated to retract or protract the bolts suitable clutch mechanism is provided comprising a pair of clutch members 14 and 15, one of which, as 14, is formed on or as a part of the loosely-mounted bevel-gear 11, while the other, as 15, is splined to the spindle and is shifted by means of a clutch-shifter 16, which is operatively connected by a lever system 17 with a pair of combination-locks 18 and 19, so that on the operation of either 20 of such locks the clutch-shifter will be operated. Each of the bolts 6 is provided with a beveled or tapered surface 20 adjacent to its end and in the rear thereof with a plane straight face 21, located to project into an opening 22, formed in the jamb of the body. This opening, one for each bolt or in the form 25 of a continuous groove, is made of sufficient depth to accommodate not merely the beveled face of the bolt, but also an appreciable portion of the plane face thereby and has its wall 23 straight or as a plane surface corresponding to the plane surface 21 of the bolt. The advantage of this construction is that as 30 the tapered faces 20 of the bolts engage the walls 23 of opening, Fig. 4, the door is with great power drawn into its seat, and the contiguous outer edge 24 of the door flush with the surface, which is usually termed the "grinding" surface around the doorway, (see 35 Fig. 5,) and when the bolts are shot completely home the plane faces 21 thereof immediately in the rear of their tapered or beveled faces 20 are brought into engagement with the corresponding plane faced wall 23 of the jamb, (see Fig. 6,) thereby relieving the bolts of any appreciable tendency to retract, since there is no longer an inclined or tapered surface in engagement with the wall of the jamb-opening to slip or creep back under vibration while still holding the door under tension. In some instances the walls of the bolt-openings could be tapered, terminating in an inwardly-extending straight surface, while the ends of the bolts could be straight and 40 without any taper.

In the present organization the bolts are not thrown merely toward their dead-centers but are shifted to and past such dead-center points, thus preventing the retraction of the bolts except by the proper means, since 70 should such bolts for any reason start to retract it will be apparent that they would continue to move in the direction in which they have been shifted past their dead-center points, which movement, however, would 75 be stopped by the walls 26 of the door, each of which walls 26 forms one of the walls of an opening through which a bolt passes and also stopped by the wall of the bolt-opening in the jamb when an independent opening is 80 provided for each bolt. From this it will be seen that to project the bolts into the jamb they are given a peculiar swinging motion (illustrated in Fig. 3) in which the final seating of each bolt in the jamb takes place only after 85 such bolt has passed beyond its dead-center, so that during its outward movement, which takes place from the line *a* up to the line *b*, at which point the bolt is in its dead-center position, as indicated by such line *b*, 90 which would pass through both the axis of the boss and the pivotal axis of the bolt, one corner, *d*, of the bolt first engages the jamb-opening wall and gradually increases such engagement until the entire bolt comes into 95 engagement therewith, at which time the shank, which is shown as a part of—that is, integral with—the bolt-head, is thrown past its dead-center, as indicated by the line *c*, at which time the opposite corner *e* of the bolt 100 extends slightly farther into the jamb-opening than the corner *d*. From this it will be immediately apparent that in order to retract the bolts at this time by further movement in this direction it would be necessary 105 to force each bolt past the inner corner 26' of the end wall 26, which would be impossible. A boss 27, preferably integral with the body of the door, is provided for engagement with the inner ends of the bolts to prevent the retraction 110 of the bolts, since in order to be retracted they must return past their dead-center lines, which is only possible by a swinging movement of the bolts, which can only be accomplished by the means provided for that 115 purpose. Thus it will be seen that the bolt mechanism is so constructed and organized that two distinct and independent means prevent their retraction—to wit, that construction which eliminates any tendency of the 120 bolts to creep back, and, secondly, that construction which permits the bolts to be shifted past their dead-center points, so that they cannot be retracted by a further inward movement. In addition to the foregoing I 125 also dog the bolts by means that has now been designated as "rim-dogging" means or bolts, since they act adjacent to the periphery of the door and which comprises a series of rotary bolts 30, projecting into the locking- 130

bolts and moved in and out by means of a gear-ring 31. These rotary bolts have pinions 32 on their ends to mesh with the gear-ring. This gear-ring is rotated by a pinion 33, carried by a bevel-gear 34, loosely mounted on the spindle 12, and to which gear movement is imparted by means of the bevel-gear 10, fixed to the worm-shaft 9 and in mesh with the loosely-mounted bevel-gear 11 upon said spindle. From this it will be seen that on the proper setting of either one of the combination-locks the splined clutch member will be shifted into engagement with the loosely-mounted bevel-gear 11 and movement imparted through the gear 10 to the main bolts, and through this gear and the gear 34 to the dogging-bolts, both of which sets of bolts will thus be operated at the same time. The openings in the main bolts for the penetration of the rotary dogging-bolts are of oblong formation, so as not to interfere with the swinging motion of the locking-bolts. After the main bolts have been fully protracted further movement thereof past their dead-center points is a pivotal movement with the dogging-bolts, as it were the pivot-points, so that owing to the position of this oblong opening it is not deemed necessary to have the ends of the dogging-bolts beveled, as heretofore deemed desirable.

For preventing the turning of the gear-ring prematurely a locking device is provided. It is shown comprising a sliding bolt 40, adapted to enter an opening in the gear-ring and is moved in and out of such opening by means of a lever 41, connected with the clutch-levers, so as to be withdrawn simultaneously with the movement of the clutch-shifter, and as the combination-locks which control this clutch-shifter are in turn controlled by time-lock mechanism it will be seen that until the running down of such timing mechanism the clutch cannot be manipulated. As both bevel-gears carried by the spindle are idle thereon, the turning of such spindle will not, until the clutch members are connected, impart movement either to the bolts or to the gear-ring, which in addition is locked against movement.

From the foregoing it will be seen that safeguards, in addition to the two hereinbefore described, are provided for against improper retraction of the bolts—to wit, the rim-dogging bolts, the gear-ring locking device, and the combination and time-lock mechanism ordinarily provided—all of which are easily and quickly operated when the time mechanism which automatically controls the working of the bolts runs down and the combination-locks are properly manipulated, but which it is believed are impossible of operation other than in a proper manner, so that the retraction of the bolts other than by a force sufficient to blow the entire structure to pieces to the injury of the contents or

a long and tedious operation in a machine-shop to grind an opening through the door, which will be of unmachineable metal, is not believed possible.

In conclusion, it is to be understood that the various details may be more or less modified without departing from the scope of my invention and that these improved bolts may be used in connection with any suitable means for operating them and in connection with various forms of safe or vault doors and whether the bolts project into or at the rear of the jamb with separate openings or as a continuous groove, &c.

Having thus described my invention, I claim—

1. A safe or vault, comprising a body, a door, and lock-controlled bolting mechanism located interiorly of the door, said body and bolts having co-operating plane faces, and one only of such co-operating parts also having a tapered face or faces, so that the door will be first drawn to its seat under tension and then held therein with the tapered face or faces entirely relieved from tension or strain, so that the bolts will be free from tendency to creep back from their bolting position.

2. A safe or vault, comprising a body having only a plane-faced bolt-engaging wall or walls, a door, lock-controlled bolting mechanism located interiorly of the door and comprising bolts each having its face nearest the front of such door both tapered and terminating in a plane face, and means for projecting said bolts so that the tapered faces thereof will first draw the door to its seat and then the plane faces of such bolts be shot into position to coact with the plane faces of the body and entirely relieve any strain on the tapered portions of the bolts, while the door is held in its jamb under tension.

3. A safe or vault, comprising a body having a plane-faced bolt-engaging wall or walls, a door, bolting mechanism comprising bolts each having a tapered face at its outer side merging at such side into a plane face, means for shooting such bolts so that the plane faces thereof will be projected beyond the periphery of the door after the door is placed under tension and entirely relieve the strain on the tapered faces of the bolts, and means in engagement with the inner ends of said bolts for preventing premature retraction thereof.

4. A safe or vault, comprising a body having only a plane-faced bolt-engaging wall or walls, a door, bolting mechanism comprising bolts having their inner ends abutting, and each bolt of which is provided nearest the front of such door with a tapered or inclined face terminating in a plane face, and means for shooting such bolts so that the door will be first drawn to its seat by the tapered portions of the bolts, and then the plane-faced portions of the bolts be shot beyond the periphery of the door adjacent thereto and into

position to engage the plane-faced bolt-engaging walls of the body and entirely disengage the tapered faces of the bolts from the body-walls, while the door is held in its jamb 5 under tension.

5. A safe or vault door having a centrally-located rocking member, a plurality of swinging, integral bolts each having its inner end directly pivoted to said member so that in 10 one position the lines of centers of said member and bolts will coincide, and means for rocking said member into position to throw said bolts to and beyond their dead-centers thereby to prevent the premature retraction 15 thereof.

6. A safe or vault door bolting mechanism comprising a plurality of swinging bolts having their inner ends abutting, means for throwing said bolts to and beyond their dead-20 centers thereby to prevent the retraction thereof, and means in position to engage the inner ends of such bolts.

7. A safe or vault door having bolt-openings, bolting mechanism comprising bolts supported for swinging reciprocatory movement, means for shifting said bolts beyond their dead-centers, further movement of said bolts in the same direction being limited by the walls of such bolt-openings, and means in 25 30 position to engage the inner ends of said bolts so that they cannot be retracted except they be swung back past their dead-centers.

8. A safe or vault door having bolt-openings, bolting mechanism comprising swinging bolts, means comprising a spindle and worm-gearing connected therewith and with the bolts for shifting said bolts beyond their dead-centers, further movement of said bolts in the same direction being limited by the walls 35 40 of such bolt-openings, and means in position to engage the inner ends of said bolts so that they cannot be retracted except they be swung back past their dead-centers.

9. A safe or vault door having bolt-openings, bolting mechanism comprising swinging bolts, means comprising a spindle, worm-gearing connected therewith and with the bolts, and clutch mechanism for controlling connection between said spindle and gearing 45 50 55 for shifting said bolts beyond their dead-centers, further movement of said bolts in the same direction being limited by the walls of such bolt-openings, and means in position to engage the inner ends of said bolts so that they cannot be retracted except they be swung back past their dead-centers.

10. A safe or vault comprising a body, a door, bolting mechanism carried by the door and comprising swinging bolts, each bolt and 60 the body having, one a plane or straight face and the other a coöperating tapered face and a straight or plane face, and means for shooting said bolts so that the plane faces of the body and bolts will engage and hold the door 65 under tension without tendency of the bolts

to creep back, and the inner ends of said bolts be carried to and beyond their dead-centers.

11. A safe or vault door bolting mechanism comprising swinging bolts each having a tapered face at its front side merging at such side into a plane face, means for shooting said bolts so that the plane faces thereof will be projected beyond the periphery of the door to engage a plane-faced jamb-wall and 70 the inner ends of said bolts be carried to and beyond their dead-centers, and means located at the inner ends of said bolts for preventing premature retraction thereof. 75

12. A safe or vault comprising a body having its jamb provided with an opening having a plane-faced wall at the side nearest the front of said body, a door, bolting mechanism comprising a plurality of bolts having their inner ends abutting and each having on 80 85 its front side a tapered face terminating in a plane face, means for swinging said bolts to and beyond their dead-centers to project the same so that the tapered faces thereof will first engage the wall of the bolt-opening and 90 draw the door to its seat and then the plane faces of said wall and bolts engage, and a stop in position to prevent inward movement of such bolts when swung beyond their dead-centers. 95

13. A safe or vault door bolting mechanism comprising swinging bolts each having at its front side a tapered face merging into a plane face, and means for shooting said bolts so that the plane faces thereof will be projected beyond the periphery of the door to engage a plane-faced jamb-wall and the inner ends of 100 105 said bolts be carried to and beyond their dead-centers, and comprising a worm-wheel plate to which the inner ends of said bolts are connected, a worm in engagement therewith, a spindle, gearing for imparting movement from said spindle to said worm, and clutch mechanism for controlling the connection between said spindle and worm. 110

14. A safe or vault door bolting mechanism comprising swinging bolts each having at its front side a tapered face merging at the rear thereof into a plane face, means for shooting said bolts so that the plane faces thereof will be projected beyond the periphery of the door to engage a plane-faced jamb-wall and the inner ends of said bolts be carried to and beyond their dead-centers, and comprising a 115 120 rocking plate to which the inner ends of said bolts are connected, a device for shifting said plate, a spindle, and means connecting said spindle and plate, and lock mechanism for controlling such connection.

15. A safe or vault door bolting mechanism comprising swinging bolts each having at its front side a tapered face merging at the rear thereof into a plane face, means for shooting said bolts so that the plane faces thereof will be projected beyond the periph- 125 130 135

- ery of the door to engage a plane-faced jamb-wall and the inner ends of said bolts be carried to and beyond their dead-centers and comprising a worm-wheel pivotally connect-
5 ed to the inner ends of said bolts, a worm-shaft having its teeth in engagement with said worm-wheel, a spindle carried by the door, a pair of bevel-gears for transmitting motion from said spindle to the shaft, one
10 fixed and the other idle, a clutch, and combination lock-controlled means for shifting one member of said clutch into engagement with the other, and means at the inner ends of said bolts for preventing the retraction thereof.
- 15 16. A safe or vault door bolting mechanism comprising bolts, means for shifting said bolts, rim-dog mechanism for dogging said bolts, comprising a series of bolts intersecting said main bolts, a gear-ring for operating
20 said intersecting bolts, and means for imparting motion to said gear-ring and comprising a spindle, a bevel-gear idle thereon and imparting motion to a pinion permanently in mesh with said gear-ring, and
25 means for communicating motion from said spindle to said bevel-gear.
17. A safe or vault door bolting mechanism comprising bolts, a worm-wheel plate to which the inner ends of said bolts are pivot-
30 ed, a worm-shaft for imparting motion to said plate, a bevel-gear fixed to said shaft, rim-dogging means for dogging said bolts, and means for imparting movement thereto and to said worm-gearing and comprising a spin-
35 dle carrying a pair of idle bevel-gears in mesh with the gear carried by said shaft, and means for making and breaking connection between said spindle and one of said bevel-gears.
- 40 18. A safe or vault door bolting mechanism, comprising swinging bolts, means for shifting said bolts to and beyond their dead-centers, and means including intersecting bolts for dogging said bolts.
- 45 19. A safe or vault door bolting mechanism, comprising swinging bolts, means for shifting said bolts to and beyond their dead-centers, and means including rotary intersecting bolts for dogging said bolts.
- 50 20. A safe or vault door bolting mechanism, comprising bolts having their ends, together with coöperating surfaces of the safe or vault body, constructed to first draw the door to its seat and then hold it there under
55 tension without tendency of the bolts to creep back, and lock-controlled spindle-operated means including intersecting bolts for dogging said bolts to prevent the retraction thereof.
- 60 21. A safe or vault door bolting mechanism, comprising bolts having their outer ends, together with coöperating surfaces of the safe or vault body, constructed to first draw the door to its seat and then hold it there under
65 tension without tendency of the bolts to

- creep back, and dogging means including rotary bolts intersecting said bolts to prevent the retraction thereof.
22. A safe or vault door bolting mechanism comprising swinging bolts having their ends together with coöperating surfaces of the safe or vault body constructed to first draw the door to its seat and then hold it there without any tendency of such bolts to creep back, means for shifting said bolts to-
70 ward and beyond their dead-centers, and means for dogging said bolts to positively prevent the retraction thereof.
23. A safe or vault door bolting mechanism comprising swinging bolts having their outer ends together with coöperating surfaces of the safe or vault body constructed to first draw the door to its seat and hold it there without any tendency of such bolts to creep back, means for shifting said bolts to-
75 ward and beyond their dead-centers, and rim-dog mechanism for dogging said bolts to positively prevent the retraction thereof.
24. A safe or vault door bolting mechanism comprising swinging bolts having their outer ends together with coöperating surfaces of the safe or vault body constructed to first draw the door to its seat and hold it there without any tendency of such bolts to creep back, means for shifting said bolts to-
80 ward and beyond their dead-centers, means for dogging said bolts to positively prevent the retraction thereof and comprising intersecting bolts, said dogging mechanism and main bolts being operative simultaneously, and
85 means for engaging the inner ends of said bolts when in their protracted position.
25. A safe or vault comprising a body, a door, bolting mechanism comprising bolts having their outer ends together with coöperating surfaces of the safe or vault body constructed to first draw the door to its seat and then disengage and render such portions ineffect-
90 fective while holding the door under tension without tendency of the bolts to creep back, and lock-controlled means comprising intersecting devices for engaging and preventing the premature retraction of the bolts.
26. A safe or vault comprising a body having a conically-formed jamb, a door conforming to and tightly fitting such jamb, with the front surfaces around and at the end termina-
95 tion of the joint relatively flat and substantially flush, and spindle-operated bolting mechanism comprising bolts having their outer ends together with coöperating surfaces of the safe or vault body constructed to first draw the door to its seat and then hold it there under tension without tendency of the bolts to creep back and means substantially
100 as shown and described, comprising intersecting devices for engaging and preventing the premature retraction of the bolts.
27. A safe or vault door having a device supported centrally of the door, and integral,
105

swinging, radially-shiftable bolts having their inner ends directly connected with said device, so that in one position the lines of centers of said device and bolts will coincide, 5 means for throwing said bolts to and beyond their dead-centers, and means for preventing the premature retraction of such bolts.

28. A safe or vault door having swinging bolts provided with abutting portions, a device connected with said bolts and supported so that in one position the lines of centers of said device and bolts will coincide, and means for shifting said device to throw the bolts beyond their dead-centers.

29. A safe or vault, comprising a body, a door, and bolting mechanism comprising swinging bolts having abutting portions and constructed, together with coöperating surfaces of the body, to first draw the door to its seat and then hold it there under tension without tendency of the bolts to creep back from their bolting position and means for throwing said bolts to and beyond their dead-center positions.

30. A safe or vault, comprising a body, a door, bolting mechanism comprising swinging bolts having abutting portions and constructed, together with coöperating surfaces of the body, to first draw the door to its seat and then hold it there under tension without tendency of the bolts to creep back from their bolting position, a device connected with said bolts and supported so that in one position the lines of centers of said device and bolts will coincide, and means for shifting said device to throw the bolts beyond their dead-centers.

31. A safe or vault, comprising a body, a door, bolting mechanism comprising swinging bolts having abutting portions and constructed, together with coöperating surfaces of the body, to first draw the door to its seat and then hold it there under tension without tendency of the bolts to creep back from their bolting position, a device connected with said bolts and supported so that in one position the lines of centers of said device and bolts will coincide, means for shifting said device to throw the bolts beyond their dead-centers, 45 and means located adjacent to the inner end of said bolts for preventing the retraction thereof when shifted beyond their dead-centers.

32. A safe or vault comprising a body, a door, bolts supported for swinging reciprocatory movement, a device connected with said bolts and supported so that in one position the lines of centers of said device and bolts will coincide, and means for throwing 55 said bolts to and beyond their dead-centers, the walls of the bolt-openings through which the bolts pass preventing further swinging movement in the same direction.

33. A safe or vault, comprising a body, a door, bolts supported on the door for swing-

ing, radial movement, means supported in position and connected with the inner ends of said bolts so that in one position and prior to the complete locking of the door the lines of centers of said means and bolts will coincide, 70 and means for throwing said bolts off such lines of centers, said body and bolts being so constructed that the bolts will first draw the door to its seat and then hold it there under tension without tendency of the bolts to 75 creep back.

34. A safe or vault comprising a body, a door, bolts supported on the door for swinging reciprocatory movement, a rocking device supported in position and connected 80 with said bolts so that in one position the lines of centers of said rocking device and bolts will coincide, said body and bolts being so constructed that the bolts will first draw the door to its seat and then hold it there under tension without tendency of the bolts to 85 creep back, and means for swinging the bolts to and beyond their dead-centers.

35. A safe or vault comprising a body, a door, bolts supported on the door for swinging radial movement, a device pivoted centrally of the door and connected to said bolts so that in one position the lines of centers of said device and bolts will coincide, and means for swinging the bolts to and beyond 90 their dead-centers, said bolts having their outer ends together with coöperating surfaces of the body so constructed that they will first draw the door to its seat and then hold it there under tension without tendency 95 of the bolts to creep back.

36. A safe or vault comprising a body, a door, bolts supported on the door for swinging radial movement, a device pivoted centrally of the door and connected to said bolts 100 so that in one position the lines of centers of said device and bolts will coincide, means for swinging the bolts to and beyond their dead-centers, said bolts having their outer ends together with coöperating surfaces of the 105 body so constructed that they will first draw the door to its seat and then hold it there under tension without tendency of the bolts to creep back, and means for preventing the retraction of the bolts.

37. A safe or vault comprising a body, a door and bolts supported by the walls of the door adjacent to their outer ends for movement in the arc of a circle and limited in their swinging movement by such walls, a device 110 pivoted centrally of the door to which the inner ends of said bolts are pivoted, the organization being such that in one position of said device and bolts the lines of centers of said device and bolts will coincide, and means for 115 shifting said bolts to and beyond their dead-centers.

38. A safe or vault comprising a body, a door and bolts supported by the walls of the door adjacent to their outer ends for move- 120

130

ment in the arc of a circle and limited in their swinging movement by such walls, a device pivoted centrally of the door to which the inner ends of said bolts are pivoted, the organization being such that in one position of said device and bolts the lines of centers of said device and bolts will coincide, means for shifting said bolts to and beyond their dead-centers, and an integral boss for preventing the retraction of said bolts.

39. A safe or vault comprising a body having a conically-shaped jamb, a door conforming to and fitting tightly therein, bolts supported by the walls of the door adjacent to their outer ends for movement in the arc of a circle and limited in such movement by such walls a disk pivoted centrally of the door and to which the inner ends of said bolts are pivoted, the organization being such that in one position the lines of centers of said disk and bolts will coincide, means for shifting said bolts to and beyond their dead-centers, and means for preventing the improper retraction thereof, said bolts being constructed at their outer ends together with coöperating surfaces of the body to draw the door

to its seat under tension and then hold it there without tendency of the bolts to creep back.

40. A safe or vault comprising a body, a door, a series of diverging bolts located around the door and means for shooting the bolts under pressure, the body and bolts constructed to first draw the door to its seat and then hold it there under tension, such bolt and body having one plane or straight face only and the other a coöperating tapered face and a straight or plane face, so that when the bolts are first shot out the tapered face on one of said parts will draw the body to its seat and then as the tapered face passes from its region of effectiveness the plane faces will only engage and hold the door under tension thus to prevent tendency of the bolts to creep back under vibration in a manner similar to that when the tapered surfaces remain in engagement.

ORVEY PRICE.
